CLAIM

The ornamental design for a panel unit as shown and described.

DESCRIPTION

FIG. 1 is a perspective view of a panel unit showing our new design.

FIG. 2 is a front view thereof;

FIG. 3 is a rear view thereof;

FIG. 4 is an enlarged left side view thereof;

FIG. 5 is an enlarged right side view thereof;

FIG. 6 is a bottom view thereof; and,

FIG. 7 is a top view thereof.
